VAPORPROOF LIGHTING UNIT

Application filed April 4, 1929. Serial No. 352,363.

The present invention relates to vapor proof lighting units and is more particularly directed toward the provision of improved mounting devices for securing glass globes to

5 their supports.

Lighting units of the type generally designated as "vapor proof" are seldom sufficiently tight to prevent the leakage of vapors and gases into the unit through the joint between

10 the glass part and its support. The usual construction employed for this purpose comprises a support having an internally threaded part adapted to receive the threaded neck of a glass globe. The globe is threaded as 15 tightly as possible against a gasket, but this simple construction has been found to be defective in providing a gas tight joint.

The pitch of the threads on the glass is necessarily rather steep (approximately four 20 threads per inch). The threads cannot be made accurately to size and hence do not closely fit the threads on the support. The friction between these parts is high, and only a small turning effort may be employed as it 25 must be transmitted through the glass. Owing to the alternate heating and cooling of the unit when the lamp is burned and extinguished, considerable pressure differences develop between the enclosed gases and the outside atmosphere. On account of this pressure difference, the unit breathes to such an 30 extent that the enclosed gas may become vapor laden to a dangerous degree.

The present invention contemplates an improved form of fixture construction whereby the glass envelope is so securely held that the breathing of the unit through the gasket is effectively prevented.

According to the preferred form of construction the support and globe are provided with threads of different pitch and a threaded ring co-operates with both these threaded parts. Owing to the difference in pitch, there is a differential action upon the turning of the 45 ring so that the globe may be very tightly clamped in place. This tightening is brought about without applying force to turn the globe.

The accompanying drawings show, for 50 purposes of illustrating the present inven-

tion, two of the many possible embodiments in which it may take form, it being understood that the drawings are illustrative of the invention rather than limiting the same.

In these drawings:

Figure 1 is an elevational view of a vapor proof unit, with parts in section;

Figure 2 is a plan view; and

Figure 3 is a perspective view of a modified form of construction.

Vapor proof lighting units of the type contemplated by the present invention are generally connected to a conduit system through which the supply wires are brought. One of the pipes of such a system is indicated at 10. A downwardly flaring supporting number 11, generally in the form of a casting, is threaded at 12 to fit the pipe. It may, if desired, be shaped to receive a wrench so as to facilitate tightening it in place.

The lower part of the support 11 is threaded as indicated at 13 and is provided with gear teeth 14. It has a bottom flange or partition plate 15 apertured at 16 to receive a keyless socket 17. The socket is flanged as shown at 18 and provided with holes 19 to receive screws 20. The screws pass through holes in a gasket 21 and are threaded into tapped holes 22 in the support. The socket has the usual terminals at the upper side to permit connecting it to the wiring and has socket contacts to support a lamp bulb 23.

A ring 24 is threaded onto the support, the ring having a number of threads 25 at its upper end for this purpose. The ring also has interiorly disposed gear teeth 26 opposite the teeth 14 and is interiorly threaded at 27 to receive the threaded neck 28 of a closed glass globe or envelope 29. The threads 27 are of higher pitch than the threads 13.

Assuming that the stationary parts of the unit have been secured together, the ring 24 is threaded up onto the support. It is then gripped while the glass globe is threaded into place to bring the end of the globe against the gasket. This threading action cannot produce a very tight joint for reasons above referred to. To tighten the joint, one may employ a tool such as indicated at 30. It

consists merely of a handle 31 and pinion 32, the latter being adapted to engage both rows of gear teeth. When the pinion is turned in the proper direction, the ring 24 will be turned relative to the support and the glass globe, which cannot turn on account of the friction of the gasket and glass. As the ring turns it tends to thread onto the glass faster than it threads off the support, owing to the difference in pitch of the threads, and hence draws the glass more tightly against the gasket. This joint is much tighter than can be obtained by twisting the globe itself. The joint is gas tight, and in order to permit the unit to breathe through the conduit system, there may be provided a suitable passage way such as the drilling 33 in the socket body 17.

In the modified form of construction shown in Figure 3, the ring 24a is provided with notches 34 so that one may employ a tool, such as a screwdriver, to tighten the ring. The shank of the tool may be placed in the notch 34 and the end of the tool engaged with the teeth or notches 35 on the supporting member 11a.

It is obvious that the invention may be embodied in many forms and constructions within the scope of the claims, and I wish it to be understood that the particular form shown is but one of the many forms. Various modifications and changes being possible, I do not otherwise limit myself in any way with respect thereto.

What is claimed is:

- 35 1. The combination with a closed glass envelope having a threaded neck, of a ring threaded onto the neck, a support threaded into the ring, and a gasket interposed between the support and neck of the glass envelope, the threads between the ring and the neck and the support being of different pitch whereby a differential action is obtained by turning the ring while the support and envelope are stationary.
- 40 2. The combination with a closed glass envelope having a threaded neck, of a ring threaded onto the neck, a support threaded into the ring, and a gasket interposed between the support and neck of the glass envelope, the threads between the ring and the neck and the support being of different pitch whereby a differential action is obtained by turning the ring while the support and envelope are stationary, the ring and support having a co-operative tool engaging device to facilitate tightening the parts.
- 45 3. The combination with a closed glass envelope having a threaded neck, of a ring threaded onto the neck a support threaded into the ring, and a gasket interposed between the support and neck of the glass envelope, the threads between the ring and the neck and the support being of different pitch whereby a differential action is obtained by

turning the ring while the support and envelope are stationary, the ring and support having gear teeth to receive a tightening device having a pinion engageable with the teeth.

4. A vapor proof lighting unit comprising a closed glass envelope having a threaded neck, a hollow support threaded at the upper end for connection to a conduit system, and threaded at its lower end, a ring threaded on to the support and having threads to receive the neck of the envelope, and a gasket interposed between the support and envelope, the threads on the lower end of the support and on the neck of the envelope being slightly different whereby a differential action is obtained upon turning the ring to securely clamp the envelope in place, there being a gas passage leading to the upper part of the support to ensure breathing of the unit through the conduit system.

5. A vapor proof lighting unit comprising a closed glass envelope having a threaded neck, a hollow support threaded at the upper end for connection to a conduit system, and threaded at its lower end, a ring threaded on to the support and having threads to receive the neck of the envelope, a gasket interposed between the support and envelope, and a lamp socket secured to the support and holding the gasket to the support, the threads on the lower end of the support and on the neck of the envelope being slightly different whereby a differential action is obtained upon turning the ring to securely clamp the envelope in place, there being a gas passage leading to the upper part of the support to ensure breathing of the unit through the conduit system.

6. A vapor proof lighting unit comprising a closed glass envelope having a threaded neck, a hollow support threaded at the upper end for connection to a conduit system, and threaded at its lower end, a ring threaded on to the support and having threads to receive the neck of the envelope, a gasket interposed between the support and envelope, and a lamp socket secured to the support and holding the gasket to the support, the threads on the lower end of the support and on the neck of the envelope being slightly different whereby a differential action is obtained upon turning the ring to securely clamp the envelope in place, the socket being provided with a ventilation hole to ensure breathing of the unit through the conduit system.

7. In combination, a glass envelope having a threaded neck, a support having a lower portion of substantially the same diameter as the neck and threaded in the same direction at a slightly finer pitch, and a ring having its lower portion interiorly threaded to fit the neck and its upper portion interiorly threaded to fit the support.

8. In combination, a glass envelope having a threaded neck, a support having a lower portion of substantially the same diameter as the neck and threaded in the same direction at a slightly finer pitch, and a ring having its lower portion interiorly threaded to fit the neck and its upper portion interiorly threaded to fit the support, the support having a row of gear teeth and the ring having a row of gear teeth opposite these on the ring, said gear teeth being adapted to receive a pinion for the purpose of tightening the glass part in place.

Signed at New York city, in the county of New York and State of New York, this 3rd day of April, 1929.
